CHANCE AND DISPENSING DEVICE

Donald M. Dickson, Gary, Ind.

Application June 4, 1935, Serial No. 24,949

6 Claims. (Cl. 273—139)

This invention relates to chance and dispensing devices and has for an object to provide a device of this character of the "punch board" type wherein there is provided a board having concealed detents which may be punched loose or dislodged to eventually release a merchandise or other character of prize when the key detent is dislodged.

A further object is to provide a device of the nature indicated which may be used as a medium for stimulating sales in stores and which will be formed of a few, inexpensive parts so constructed that after each dispensing operation the device may be discarded if desired or may be reloaded.

15 A further object is to provide a novel bolt for releasing the prize carrier and which may be located at any predetermined position within the area covered by the detents so that the detents may not be released in any regular order to free the bolt and allow the dispensing carrier to operate, thus providing the element of chance.

With the above and other objects in view the invention consists of certain novel details of construction and combinations of parts hereinafter 25 fully described and claimed, it being understood that various modifications may be resorted to within the scope of the appended claims without departing from spirit or sacrificing any of the advantages of the invention.

30 In the accompanying drawings forming part of this specification,

Figure 1 is a perspective view of a chance and dispensing device constructed in accordance with the invention.

35 Figure 2 is a cross sectional view taken on the line 2—2 of Figure 1 looking in the direction of the arrows.

Figure 3 is a longitudinal sectional view taken on the line 3—3 of Figure 2 looking in the direction of the arrows.

40 Figure 4 is a cross sectional view taken on the line 4—4 of Figure 3.

Figure 5 is an edge elevation of the prize carrier.

45 Figure 6 is a detail perspective view of the latch.

Referring now to the drawings in which like characters or reference designate similar parts in the various views, the frame or body of the device is shown to comprise a back wall 10 upon the 50 front face of which are formed a chamber 11 and a slot 12 disposed at a right angle to the chamber and communicating with the chamber. The chamber is formed with an extension 13 at the upper end and with a substantially rectangular depression 14 in the bottom near the upper end

as shown in Figure 2. Also a guide rib 15 extends upwardly from the lower end wall 16 of the chamber to guide the prize carrier 17 and also provide a space 18 through which the prize winner may remove the merchandise or other prize article when the carrier is in dispensing position.

The carrier 17 is preferably formed of thin sheet metal provided at the top with a rearwardly extending guide lip 19 which is adapted to fit in the depression 14 and coact with the guide rib 15 in directing sliding movement of the carrier. The carrier is provided with a forwardly extending ledge 20 at the bottom to support the article of merchandise or other prize package. A substantially U-shaped leaf spring 21 is mounted in the chamber 11 above the carrier and exerts downward pressure upon the carrier to push the carrier to dispensing position. A pair of staples 22 secure the spring to the wall of the chamber and in the present embodiment of the invention 20 the stationary leg of the spring is provided with a terminal prong 23 which is driven into the wall of the chamber and coacts with the staples in mounting the spring.

The carrier is provided in one edge with a 25 plurality of semicircular notches 24 to interchangeably receive the substantially circular terminal 25 of a latch 26 which is pivoted intermediate the ends as shown at 27 to the bottom wall of the chamber. A leaf spring 28 is fixed 30 at one end to the bottom wall of the chamber by a staple 29 or other connector and the free end of the leaf spring engages in rear of a terminal finger 30 formed on the latch adjacent to the circular terminal 25 and exerts outward 35 pressure on the latch tending to disengage the terminal 25 from the notch 24 and free the carrier to be pushed downward by its spring 21. The latch 24 is held in locking position against the tension of its controlling spring 28 by means 40 of a bolt 31.

The bolt 31 is slidably fitted in the above mentioned slot 12 and is provided in the upper edge with a notch 32 which provides a finger 33 at the end of the bolt. The finger 33 overlaps a 45 similar finger 34 formed on the latch 26, and holds the latch locked to the carrier. When the bolt is freed the finger 34 of the latch shoves the bolt 31 laterally toward the carrier until it abuts a stop 35 disposed between the carrier 50 and the bolt. The bolt is held withdrawn into the slot 12 to hold the latch in locking position by means of a plurality of detents 36.

The detents 36 may be in the nature of pins, sales tickets or other elements carried in open- 55

ings 37 in the back wall or board 10. As shown best in Figure 3 approximately one-half the area of the board to the left of the carrier is devoted to mounting the detents 36 so that certain rows of the detents will naturally pass through the bolt 31 and lock the bolt to the board against endwise thrust of the latch. The detents are punched out with a pin, punch or in any other manner, and it will be seen that when the last detent holding the bolt is dislodged, the bolt is freed and permits the latch 26 to be swung on the pivot 27 by the controlling spring 28 and disengage the terminal 25 from the notch 24 in the carrier.

A front wall or board 38 is secured in any preferred manner to the rear wall or board 10 and forms a closure for the chamber 11 and slot 12. The front board covers and conceals the carrier, the latch, and the bolt and is provided with openings 39 which align with the openings 37 in the rear wall to receive the detents 36. A window opening 40 is formed in the front wall 38 and is provided with a transparent pane 41 which may be mounted upon stop strips 42 secured to the longitudinal edges of the window opening, as shown in Figure 4, and a stop strip 43 secured to the top edge of the window opening, as shown in Figure 2. Brads 44 or other securing devices may be driven into the front board around the edges of the window opening to clamp the pane in position against the stop strips. The pane is of sufficient length to extend to the ledge 20 on the carrier 17 when the carrier is in raised position so that the prize package may be visible but may not be surreptitiously removed without breaking the pane. Below the pane, as heretofore mentioned, a space exists through which the contents of the carrier may be removed by the prize winner when the carrier is pushed to dispensing position by its spring 21.

In operation, when the device is used to stimulate trade, the detents may have different values corresponding to sales tickets and when a sale is made the customer may punch out one or more of the detents to correspond to the amount on the sales receipt. Since the detents extend over a wide area and are identical there is no possibility of any systematic punching out of the detents in any regular order so that thus the element of chance is provided. When the key or last detent which holds the bolt is punched out, the bolt is freed and releases the latch to be moved by its controlling spring from locking engagement with the carrier. The carrier is immediately pushed by its controlling spring to dispensing position below the pane 41.

In manufacturing the device the slot 12 may be placed at different localities in different boards and the plurality of notches 24 in the carrier will thus permit one carrier to be manufactured and fit all of the various boards since whenever the slot 12 is arranged in a different position from that shown in Figure 3 it is simply necessary to dispose the latch 26 in a corresponding position, under which circumstances the terminal 25 of the latch will engage in a different notch 24 than shown in Figure 3.

From the above description it is thought that the construction and operation of my invention will be fully understood without further explanation.

What is claimed is:

1. Apparatus of the class described comprising a frame having a chamber and a slot extending transversely to the chamber, a spring pressed dispensing carrier slidable longitudinally in the chamber, a locking bolt slidably fitted in the slot, a spring pressed latch in the chamber engaging the bolt and the carrier and normally holding the carrier at one limit of its movement in the chamber, and a plurality of manually releasable detents locking the bolt at one limit of its movement in the slot. 5 10

2. Apparatus of the class described comprising a frame having a chamber and a transverse slot entering the chamber, a carrier disposed at one end of the chamber, a spring tending to push 15 the carrier to the opposite end of the chamber, a locking bolt in said slot, a pivoted latch in the chamber operatively connected to the bolt and interlockingly engaging said carrier, a spring tending to swing the latch out of engagement 20 with the carrier and to move the bolt endwise, and a manually releasable detent locking the bolt stationary on the frame against the tension of the latch controlling spring.

3. Apparatus of the class described comprising 25 a frame having a chamber and a transverse slot entering the chamber, a carrier disposed at one end of the chamber and spring pressed to move bodily to the opposite end of the chamber, a transparent closure for the chamber exposing 30 the carrier and terminating short of the lower end of the chamber to permit access to the carrier when the carrier is moved by its spring beyond the closure, a pivoted latch engaging said carrier, a bolt in said slot engaging the latch, 35 a manually releasable detent holding the bolt in position to engage the latch with the carrier, and a spring for removing the latch from engagement with the carrier upon release of the bolt by displacement of said detent. 40

4. Apparatus of the class described comprising 45 a frame, a spring pressed carrier on the frame, a locking latch for the carrier, a bolt normally holding the latch engaged with the carrier, a manually releasable detent normally holding the bolt at one limit of its movement, a spring operatively engaging the latch to disengage the latch from the carrier upon removal of said detent, a closure concealing the carrier, and guides between the carrier and the frame for directing 50 sliding movement of the carrier under pressure of its controlling spring to a position beyond the closure.

5. A device of the class described comprising 55 a frame having a plurality of transverse openings, detents in said openings, a locking bolt engaged by certain of the detents, a carrier on the frame for dispensing an article, and means between the bolt and the carrier and operatively connected to the bolt and the carrier for moving 60 the carrier bodily on the frame to dispensing position when certain of said detents are removed from said openings.

6. A device of the class described comprising a frame, a spring pressed carrier on the frame, a 65 transparent closure on the frame in registration with the carrier, means for sliding the carrier bodily beyond the closure to dispensing position, a plurality of pins removably secured in said frame laterally of the carrier, and means energized by displacement of certain of the pins to move the carrier to dispensing position. 70

DONALD M. DICKSON.
